UNITED STATES PATENT OFFICE.

GUY C. WILKINSON, OF SYRACUSE, NEW YORK, ASSIGNOR TO SYRACUSE WASHING MACHINE CORPORATION, OF SYRACUSE, NEW YORK, A CORPORATION OF NEW YORK.

CLOTHES WRINGER.

Application filed March 11, 1924. Serial No. 698,386.

This invention relates to wringers of the feed roller type adapted to be used more particularly in connection with power-driven washing machines and involves the 5 use of a roller-supporting frame hinged at one end to swing in a horizontal plane to different angles about the axis of a vertical drive shaft to and from a position over the washing or rinsing vats or other receptacles 10 which may be used in connection with the washing machine although it is evident that the novel features of the invention may be used in connection with stationary wringers.

In wringers of this type, suitable means is 15 provided for reversing the direction of rotation of the rollers for feeding the wet articles from one receptacle into another, and under these conditions, it is desirable to provide what is commonly known as a 20 water-board or drainage plate for guiding the articles and for conducting the expressed water over the intervening space between the receptacles.

This is particularly true in wringing the clothes from the washing vat to the rinsing vat and vice versa, and in many instances, particularly in wringing thick and heavy articles, the volume of water expressed from the clothes at the entrance side of the rollers 30 frequently overflows the sides of the water-board unless some provision is made for confining the water within the edges of the water-board and one of the objects of my invention is to not only provide the longitudinal edges of the water-board with up- 35 standing flanges, but also to provide the board with one or more transverse slots near the ends thereof to cause the greater volume of the water to drain therethrough 40 into the rinsing vat which is usually placed upon the floor at one side of the washing vat and at the in-feed side of the wringer.

Another object is to enable the water-board to be adjusted in the wringer frame 45 transversely of and beneath the wringer in an inclined position at one side or the other of the frame for directing the clothes downwardly according to the direction of rotation of the rolls.

50 A further object is to provide means for releasably locking the water-board in either of its adjusted positions against endwise movement or vertical vibration.

The upper roller is usually spring-pressed against the lower roller and the tension of 55 the spring adjusted by means of a screw, and another object of the invention is to provide a movable support for the screw and to hold said support in operative position by means of a spring-retracted latch 60 adapted to be instantly released by the operator to release the spring pressure upon the upper roller in case of accident or for any other reason requiring quick release of 65 such pressure, the specific object of the self-retracting latch being to automatically re-engage the screw support when the latter is returned to its operative position.

Other objects and uses relating to specific parts of the wringer will be brought out in 70 the following description.

In the drawings:

Figure 1 is a perspective view of a wringer embodying the various features of my invention.

Figure 2 is a longitudinal vertical sectional view of the same wringer taken on line 2—2, Figure 1.

Figure 3 is a transverse vertical sectional view taken on line 3—3, Figure 1, and Figure 4 is a perspective view of the detached water-board.

Figure 5 is a transverse vertical sectional view taken in the plane of line 5—5, Figure 2.

As illustrated, this wringer comprises an inverted U-shaped hollow frame —1— having an upwardly arched top portion —2— and opposite end legs —3— and —3'— which are connected near the bottom by a tie rod —4— to stiffen them against relative endwise movement and at the same time leaving a clear open space through the frame from front to rear between the rod —4— and top portion —2— for the passage of clothes therethrough.

A pair of wringer rolls —5— and —5'— are mounted in the frame between the end legs —3— and —3'— and some distance above the tie rod —4— with their meeting faces registering with the opening through the frame.

The opposite ends of these rollers are journaled in anti-friction bearings —6— which together with a pair of pressure bars —7—, are mounted in vertical guide-

ways —8—, the bearings —6— for the lower roller —5— being adapted to rest upon underlying supporting flanges —9— projecting inwardly from the adjacent portions 5 of the legs —3— and —3'—.

The inner edges of the flanges —9— extend beyond and below the adjacent ends of the lower roller —5— and are curved downwardly for deflecting any water which may 10 lodge thereon on to an underlying water-board —10—.

The shafts or end trunnions for supporting the rollers —5— and —5'— are journaled in their corresponding bearings —6— 15 while the central portions are covered as usual, with rubber or other resilient material capable of frictionally feeding the laundry articles between them.

The bearings —6— for the ends of the 20 rollers are substantially identical, each consisting of an inner sleeve —11— and an outer ring —12— journaled on the periphery of the sleeve through the medium of anti-friction rollers —13— as shown more clearly 25 in Figure 5.

The end rings —12— of the lower bearings —6— rest directly upon the adjacent flanges —9— and also against the inner faces of the opposed guides —8— while the rings 30 —12— for the upper bearings —6— are adapted to ride in said guides, it being understood that the upper roller —5'— normally rests directly upon the periphery of the lower roller —5— and that it is free to move 35 vertically to compensate for varying thicknesses of articles which are to be wrung between the rollers.

The pressure bars —7— are also movable 40 vertically in the adjacent guides —8— and bear directly upon the upper faces of the adjacent rings —12— of the upper bearings —6—.

An upwardly arched leaf spring —14— 45 extends lengthwise of and within the upper portion of the frame —1— and has its ends resting upon the upper faces of the pressure bars —7— while the central portion is engaged by a screw —15— in a movable section —16— of the top —2— of the frame.

The movable section —16— is pivoted at 50 —17— to the top portion —2— of the frame at one side of a screw —15— and is provided with a shoulder —18— at the opposite side of said screw adapted to be engaged 55 by a latch lever —19— which in turn is pivoted at —20— to the top of the frame —1— at the same side of the screw as the shoulder —18— and is spring pressed into engagement with said shoulder by means of a 60 flat spring —21—, the latter being held in operative position on the underside of the top portion —2— by suitable lugs —22—, Figure 2.

The pivotal pins —17— and —20— for the 65 movable section —16— and latch lever

—19— respectively, are located within the top portion —2— of the frame —1— while the members —16— and —19— are movable in an opening —23— in said top.

That is, when the section —16— is closed, 70 it forms a continuation of the top —2—, while the lever latch —19— extends through the opening —23— to overhang a portion of the top —2— lengthwise thereof as shown in Figure 2 to form a handle whereby it may be depressed against the action of the spring —21— to release the movable section —16— and thereby to release pressure of the spring —14— upon the pressure bars —7— thus 75 permitting the upper roller —5'— to move 80 freely toward and away from the lower roller —5— without displacing the spring —14— from its operative position.

In restoring the movable section —16— with the screw —15— thereon to its closed 85 position, its shoulder —18— engages a portion of the lever latch —19— above its pivot —20— thereby rocking the lever inwardly against the action of the spring —21— until the shoulder —18— is interlocked with a 90 companion shoulder —18'— on the latch lever directly over the pivot —20—.

It will be seen from the foregoing description that the closing of the movable section —16— by hand automatically interlocks it with the latch lever —19— but just preceding this closing movement it is preferred to unscrew the screw —15— sufficiently to avoid the excessive resistance of the spring —14— and as soon as the movable section is locked by the lever —19—, the screw —15— may be again tightened to impart the desired tension to the spring —14— and corresponding pressure upon the upper roller —5— through the medium of the pressure bars —7—, the upper end of the screw being provided with a handle —24— by which it may be turned.

A gear case —25— is bolted or otherwise secured to one end of the wringer frame 110 —1— for receiving and supporting a drive shaft —26— and suitable gearing for transmitting rotary motion from said drive shaft to the lower roller —5— and from said roller to the upper roller —5'—, said gear case 115 being provided with a vertical hub —27— having a socket open at its lower end for receiving a supporting sleeve —28— which is generally fixed to the frame of the washing machine against rotation and is seated against the upper wall of the socket in the hub —27— to permit the wringer as a whole 120 to swing horizontally about the axis of the drive shaft —6— and supporting tube or post —28— as may be required for wringing clothes from the washing vat to the rinsing vat or other tubs and vice versa.

The wringer is held in different angularly 125 adjusted positions by means of a locking bolt —29— which may be withdrawn by hand 130

from any one of its plurality of openings in the post —28— against the action of a retracting spring —30— to permit the horizontal swinging movement of the wringer, 5 the spring —30— serving to automatically restore the locking bolt —29— to its locking position when registered with any one of the openings in the tube —28—.

The drive shaft —26— is provided with a 10 double end clutch member —31— splined thereon for axial movement and to rotate therewith and is movable from a neutral position into and out of engagement with one or the other of a pair of beveled pinions —32— at opposite ends of the clutch-member —31—, said pinions being engaged with diametrically opposite faces of a gear —33— which in turn is operatively connected to the shaft of the lower roller —5— to transmit rotary motion thereto when the shaft —26— is rotated and the clutch member —31— is engaged with either one of the clutch pinions —32—.

That is, when the clutch member is engaged with one of the pinions, the wringer rolls —5— and —5'— will be rotated in one direction and when engaged with the other pinion will be rotated in a reverse direction.

The clutch member —31— is provided 30 with an annular groove which is engaged by an eccentric member —34— on the inner end of a rock shaft —35— which is journaled in the outer wall of the gear case —25— and is provided with a handle —36— 35 by which it may be rocked in reverse directions for engaging the clutch member —31— with either of the pinions —32— according to the direction in which it may be desired to rotate the wringer rolls —5— and —5'—.

40 The water-board —10— is movable transversely of the wringer rolls in the space between the tie rod —4— and lower roll —5— and is provided with lengthwise flanges —37— secured to the underside thereof near 45 its longitudinal edges for reinforcing purposes and also to ride upon the upper face of the rod —4— for supporting the water-board in its operative position, said flange being provided with notches —42— for receiving the rod —4— for holding the water board against endwise movement when adjusted mainly to one side or to the other side of the rollers.

This water-board —10— extends laterally 55 beyond the inner edges of the flanges —9— and has its opposite longitudinal edges provided with upturned flanges —38— for confining any water which may lodge on the board within the edges thereof and causing 60 it to drain from the ends.

This end drainage is further facilitated by drawing the ends of the flanges —38— inwardly toward each other so that the widths of the ends of the water board are slightly 65 less than the intermediate portion and causes

the water to drain toward the longitudinal center and into the slots —40—.

In some instances, particularly when passing heavy articles from the rinsing vat through the wringer into the washing vat 70 or other receptacle, the volume of water expressed by the wringers is too great to be carried off by a plain water-board even though confined more or less by the flanges —38—, resulting in overflow of excess water 75 from the water-board on to the floor and in order to overcome this difficulty, the water-board is provided near its ends with transverse slots —40— between the flanges —38— to permit a considerable quantity of water 80 expressed by the wringer rolls to pass therethrough and into the underlying rinsing vat or other receptacle, and thereby preventing the lateral overflow over the flanges —38— at the low end of the water-board. 85

As previously stated, the water-board —10— is slidable endwise transversely of and upon the supporting rod —4— and is provided with slots —40— mainly to one side or the other of the wringer rolls —5— 90 according to the direction of feed of the wet articles through the wringer and is adapted to be supported in a tilted position under the rolls, and is provided with stop shoulders —41— at the ends of the flanges —37— for limiting such movement, portions of said flanges just inside of the stops being recessed at —42— to receive the rod and to cooperate therewith in holding the water-board against accidental endwise movement. 95 100

In other words, the stops —41— are arranged in spaced relation lengthwise of the water-board to permit the desired adjustment of said water-board mainly to one side or the other of the wringer rolls and at the same time, the walls of the recesses —42— form bearings for engaging the rod —4— and permitting the tilting of the water-board about the axis thereof, the object of the tilting movement being to drain the water expressed by the rollers back into the receptacle from which the articles are fed through the wringer. 110

Suitable means is provided for releasably holding the water-board in its adjusted and tilted position, mainly at either side of the wringer rolls and for this purpose is provided a pair of pawls or detents —44— pivoted at —45— to opposite sides of the frame —1— some distance above the horizontal plane of the lower wringer roll —5— and having their lower ends provided with arms —46— spaced apart a distance corresponding to the spacing of the central portions of the flanges —38— for engaging in notches —47— and —47'— in the upper edges of said flanges.

These notches —47— and —47'— are arranged in close proximity to each other but in reverse order and substantially midway

between the stops —41— so that when the water board is adjusted to one position as shown by full lines in Figure 3, the lower ends —46— of the corresponding pawl —44— will engage in the notches —47—, but when the water-board is shifted mainly to the opposite side of the wringer rolls as shown by dotted lines in the same figure, the lower ends of the opposite pawl —44— will 10 be engaged in the notches —47'—.

Owing to the fact that the opposite ends of the flanges —38— are drawn inwardly or closer to each other than their central portions, the lower ends of the pawls —44— 15 at the higher side of the water table will drop down at the outer sides of the adjacent ends of the flanges by reason of the fact that the distance between the arms —46— of each pawl —44— is substantially equal to the 20 distance between the flanges at the center of the water-board and greater than the distance between the flanges at the ends of said water board.

The portions —44— are provided with 25 lengthwise bars —50— connecting the arms —46— and forming stops or abutments for engaging the flanges —38— and limiting the upward swinging movement of each end of the water-board as the other end is tilted 30 downwardly.

It will be observed that the ends of the water-board begin to contract unequal distances from the stops —41— and also from the shoulders —47— and —47'— of the 35 flanges —38— and that the contracted portion at one end is somewhat longer than that of the opposite end, the object of which is to permit the longer end to extend farther into the washing vat for effectively draining the 40 water from the wringer back into said vat while the shorter contracted end is adapted to overhang a rinsing vat or other receptacle from which the wet clothes are re-wrung through the wringer into the washing vat 45 or other receptacle and owing to the fact that the rinsing vat is usually placed directly upon the floor or considerably lower than the washing vat, it is desirable to provide the corresponding end of the water-board with 50 the extra drainage slot —40— to prevent the excess water from overflowing the ad-

jacent portions of the flanges —38— on to the floor.

Rotary motion is transmitted from the shaft of the roller —5— to the roller —5'— 55 by means of gearing —52— arranged to allow limited vertical movement of the roller —5'— relatively to the roller —5— without disengagement.

The structure shown and described is 60 found to be particularly efficient, but it is evident that various changes may be made in the structural details without departing from the spirit of this invention.

I claim:—

1. In a wringer, a drain board having upturned flanges along its opposite ends and lengthwise slots through its bottom near its opposite lengthwise sides, the portions of the end flanges at opposite ends of the slots 70 being deflected inwardly to deflect the drainage water toward the slots.

2. In a wringer, a frame having a fulcrum for a drain board, and a drain board 75 slideable transversely of and upon the fulcrum and provided with stops at unequal distances from the longitudinal center of the drain board for engaging said fulcrum and limiting the sliding movement of the drain board in opposite directions on the fulcrum 80 to allow said drain board to project farther to one side of the fulcrum when adjusted to one extreme position than to the opposite side when adjusted to the other extreme position for the purpose described. 85

3. In a wringer, a frame having a fulcrum for a drain board, a drain board slideable transversely of and upon the fulcrum and provided with upturned flanges along its opposite ends, stops on the drain board at 90 unequal distances from its longitudinal center, said upturned flanges having shoulders substantially equal distances from their respective stops, and detents hinged to the frame at opposite sides of the fulcrum for 95 engaging their respective shoulders and holding the drain board in its extreme positions of adjustment as limited by said stops.

In witness whereof I have hereunto set my hand this sixth day of March, 1924.

GUY C. WILKINSON.
